UNITED STATES PATENT OFFICE.

WILLIAM E. BALL, OF ZANESVILLE, OHIO, ASSIGNOR OF ONE-HALF TO
J. FRANKLIN BURROWS, OF SAME PLACE.

DESIGN FOR A LAMP-SHADE HOLDER.

SPECIFICATION forming part of Design No. 26,022, dated September 15, 1896.

Application filed July 29, 1896. Serial No. 600,989. Term of patent 7 years.

To all whom it may concern:

Be it known that I, WILLIAM E. BALL, a citizen of the United States, residing at Zanesville, in the county of Muskingum, State of Ohio, have invented and produced a new and original Design for a Lamp-Shade Holder, of which the following is a specification, reference being had to the accompanying drawing, which is a perspective view of a lamp-shade holder made according to my design.

My lamp-shade holder is made of a piece of wire having a ring A, formed in the center of said wire, from which rises the remainder of the wire, forming a partial ring B, from which extends two curved parts C, whose upper portions near the ends are twisted, as shown at D, and whose extremities are first bent outward, as at E, and then bent into hooks F. It is designed to use this as an advertising means by setting an advertising

card between the rings A B, which will securely hold said card in place. The hooks F are to be set over the edge of a lamp-chimney, and the holder can thus be readily attached or detached. The shade held by the rings may be of any desired shape or size, but I prefer to make it of about the size of or a trifle larger than the larger ring, so that the latter will form a kind of frame around its edge.

What I claim as new is—

The design for a lamp-shade holder, substantially as herein shown and described.

In testimony whereof I affix my signature, in the presence of two witnesses, this 27th day of July, 1896.

WILLIAM E. BALL.
